CAR LOADING DEVICE FOR BALLAST
CLEANINGS

Charles A. Gill, Reading, Pa.

Application September 16, 1937, Serial No. 164,215

6 Claims. (Cl. 209—257)

This invention relates to a car loading device for use with a ballast excavator and screening machine.

It is an object of the invention to provide a device to receive the dirt screened out of railway ballast by a machine that screens the ballast and returns the clean ballast to the right of way; to convey the dirt thus screened to a following car; and to fully load the car with the dirt.

10 It is a further object of the invention to provide a device of the character referred to which, utilizing a conveyor fixed in place on a car, will fully load the car from end to end, and which may be operated with either end adjacent the ballast cleaner.

15 It is a further object of the invention to provide an elevating conveyor especially adapted to the service.

Further objects of the invention will appear from the following description when read in the light of the accompanying drawings showing 20 illustrative embodiments of the invention and in which:

Figure 1 is a perspective view diagrammatic in character of a structure embodying the invention;

Fig. 2 is a section on broken line 2—2 of Figure 3, upon an enlarged scale;

Fig. 3 is a detail side elevation of the dirt receiving and elevating conveyor;

25 Fig. 4 is a detail section on line 4—4 of Figure 3, on an enlarged scale;

Fig. 5 is a plan view of the structure of Figure 3;

Fig. 6 is a vertical transverse section on line 25 6—6 of Figure 5;

Fig. 7 is a plan view of a dirt-receiving car and loading conveyor, broken away to decrease its length; and

30 Fig. 8 is a detail side elevation of the structure of Figure 7, with portions broken away.

The device of the present invention is designed to operate upon the dirt removed from railway ballast by the device disclosed in applicant's co-pending application, Serial No. 116,174, filed December 16, 1936, the present application being a continuation in part of said prior application.

As shown in the said prior application the excavating machine is mounted on the car 10 shown herein and has means to deliver the excavated material to the screen 11; means to shake the screen by movement on rollers 12, 13; and means to drive the car 10 through shaft 14, Figure 5. The clean ballast passes from the end

of the screen 10 to be returned to the right of way.

Dirt passing through the screen falls into hopper 15 of boot 15', Figure 6, by which it is delivered to transversely placed elevating conveyor 16 comprising buckets 17 which delivers to elevating conveyor 18.

The elevator 18, mounted on car 10, projects rearwardly to overhang a dirt car 19 and delivers, as shown, to a hopper 20 carried by a screw conveyor 21 fixedly mounted on car 19 by means of struts 22, and is placed in a somewhat diagonal position because the conveyor 18 is out of center on car 10. A hopper 20 is provided at each end of conveyor 21 in order that the car 19 may be loaded from either end.

To load the car 19 from end to end by means of the simple screw conveyor shown, the bottom of the trough of the conveyor is formed with an open slot, as shown, from the point 23, Figures 7 and 8, to the point 24. The altitude of the conveyor above the car is so chosen that the expected angle of repose of the dirt will cause the car to be substantially completely filled to the upper edges of its sides. The points 23 are likewise so chosen with relation to the end closures of the car. The result of this structure is that the dirt will spill through the loading end of the slot until it piles up to close the first portion of the slot, thus in effect forming a bottom of the conveyor trough, which closure will progress along the conveyor until the car is completely loaded. The car 19 is desirably a dump car of any preferred type.

To drive the conveyors of the device a drive shaft 25 is shown driven by bevel gears 26 and controlled by clutch 27. The gears 26 are desirably driven by the mechanism which causes oscillation of the screen 11.

To drive the transverse elevating conveyor 16, a sprocket wheel 28 is shown fixed on shaft 25, about which sprocket wheel chain 29 passes to drive sprocket 30, fixed on the upper shaft 31 of conveyor 16.

To drive conveyor 18, shaft 32, driven by angle gears 33 from shaft 25 is shown extending parallel with the conveyor to drive the upper shaft 34, through bevel gears 35.

To drive conveyor 21, a shaft 36 is shown driven through universal joint 37, by spur gears 38 from shaft 32. The connection between shaft 36 and the shaft of conveyor 21 is shown as a splined telescopic joint 39 and universal joint 40. The universal joint 40 and female splined socket for joint 39 is applicable at either end of

the shaft of conveyor 21 in order that the said conveyor may be connected to drive shaft 30 at either end and the car 19 will never need to be turned by a turn table in order to be loaded.

5 When the car 19 is disconnected for dumping the squared or splined socket 39 will be automatically released from the shaft of conveyor 21 and as readily again coupled, or a spare car equipped with a conveyor 21 may be substituted.

10 It is obvious that a screw conveyor may be utilized for either or each of conveyors 16 and 18.

As shown a belt conveyor is utilized comprising the belt 41, provided with flights 42 on its carrying surface and guides 43 on its inside surface.

15 The head and tail shaft and roller assembly is shown in section in Figure 4 comprising the roller 44, shaft 45 and roller bearings 46 supported on the angle frame members 47, 48. Said frame members are shown as supported on standards 20 49 and by braces 50, 51, carried by the car 10. Means to adjust the tension of the belt are shown at 52, Figure 3, the shaft of the tail roller being slidably mounted, as usual with belt conveyors, for this purpose.

25 The upper intermediate guide rollers 53, and the return flight or lower intermediate guide rollers 54 are formed as shown in the sectional view Figure 2, also supported in roller bearings carried by the angle members 47, 48. To pass 30 the guide members 43, the rollers 44, 53 are each formed with circumferential grooves 56 which guide members passing through the grooves preserve the proper centering of the belt. The flights 42 are accommodated by the circumferential grooves, or recesses, 57 (Figure 2) in the lower guide rollers 54.

A boot 58, Figures 3 and 6, is provided at the tail of the conveyor 18, shown as supported by the angle frame members 59 of conveyor 16.

40 Rubber skirts 60 are shown at the lower side edges of the boot 58 hanging closely adjacent the surface of belt 41.

To prevent escape of material from the flattening upper end of the belt 41, straps 61 are 45 shown supported by members 62 secured to the frame members 47, 48, and rubber skirts 63 are shown hanging from the straps 61 and overlying the belt.

To support the shaft 36 when a car 19 is uncoupled, a hook 64 is shown carried by frame member 47. The slip joint 39 has sufficient play to allow for yielding of the car coupling in buff or stress.

The operation will be clear from the above description. Minor changes may be made in the details of the invention from those shown, within the scope of the following claims, without departing from the spirit of the invention.

I claim:

60 1. Car loading apparatus for use with a ballast excavating and screening machine comprising in combination: a screening car to carry the screening apparatus; a dirt car to be coupled thereto; a conveyor mounted on said screening car and 65 projecting to overhang the dirt car; a second conveyor mounted on the screening car located to receive the dirt passing through a ballast screen, and to deliver the same to the first named conveyor; a distributing conveyor mounted on 70 the dirt car to receive dirt from the first named conveyor; a primary drive shaft to drive the first named conveyor; means to drive the second named conveyor from said drive shaft; means to drive the distributing conveyor from said primary 75 drive shaft; readily separable connecting means

in said last named drive means to enable the dirt car to be easily separated from the screening car; and means to drive said primary drive shaft.

2. Car loading apparatus for use with a ballast excavating and screening machine comprising 5 in combination: a screening car having screening apparatus and a drive shaft mounted thereon; an elevating conveyor mounted longitudinally thereon projecting to overhang a car attached thereto to convey dirt screened from ballast; a shaft mounted on and parallel with the frame of said elevating conveyor and extending to the upper end thereof; means applied adjacent the lower end of the last named shaft to drive the same from said drive shaft; means to 10 drive said elevator from the upper end of said parallel shaft; and drive shaft means having driving connection with an intermediate portion of said parallel shaft, including a universal joint and a splined socket to be connected to loading 15 conveyor means on said attached car.

3. Car loading apparatus for use with a ballast excavating and screening machine comprising, in combination: a railway car to carry the screening apparatus; a conveyor mounted on said car and projecting therefrom to overhang a car coupled thereto; a car to be so coupled; a distributing conveyor carried by the last named car provided with a receiving hopper at each end; drive means carried by the first named car 25 30 geared to drive the first named conveyor; a drive shaft geared to said drive means projecting over the space between the cars when coupled together; a slip joint coupling driven by said drive means; a complementary slip joint coupling associated with each end of said distributing conveyor whereby said second named car may be operatively coupled at either end with said drive shaft.

4. In a device of the class described: a railway car equipped to be coupled at either end to a car loading device; a distributing conveyor mounted on and above said car, extending longitudinally thereof; drive means at each end of said conveyor to be coupled to drive means on said loading device, said drive means comprising 40 45 one portion of a slip joint connection; a screen car provided with means to be coupled to either end of the first named car; ballast screening apparatus mounted on said screen car; conveyor means carried by said screen car positioned to receive dirt screened from ballast as it passes through said screening apparatus, and extending to deliver to the conveyor on the first named car; and power means on said screen car connected to actuate said screening apparatus, said dirt receiving conveyor, and a second portion of a slip joint connection to be connected to either of said first named connections.

5. In a device of the class described: a railway car equipped to be coupled at either end to a car loading device; a distributing conveyor mounted on and above said car, extending longitudinally thereof; a receiving hopper at each end of said conveyor; drive means at each end of said conveyor to be coupled to drive means on said loading device, said drive means comprising one portion of a slip joint connection; a screen car provided with means to be coupled to either end of the first named car; ballast screening apparatus mounted on said screen car; conveyor means carried by said screen car positioned to receive dirt screened from ballast as it passes through said screening apparatus, and extending to deliver to the conveyor on the first named car; and power means on said screen car connected 60 65 70 75 80 85 90 95 98

to actuate said screening apparatus, said dirt receiving conveyor, and a second portion of a slip joint connection to be connected to either of said first named connections.

6. In a device of the class described: a railway car equipped to be coupled at either end to a car loading device; a screw conveyor and trough therefor mounted on and above said car and extending longitudinally thereof; said trough having a longitudinal slot in its bottom; a receiving hopper mounted on each end of said trough; a drive connection at each end of the shaft of said screw conveyor either of which may be connected with a drive connection carried by the loading device, said drive means comprising one portion

of a slip joint connection; a screen car provided with means to be coupled to either end of the first named car; ballast screening apparatus mounted on said screen car; conveyor means carried by said screen car positioned to receive dirt screened from ballast as it passes through said screening apparatus, and extending to deliver to the conveyor on the first named car; and power means on said screen car connected to actuate said screening apparatus, said dirt receiving conveyor, and a second portion of a slip joint connection to be connected to either of said first named connections.
